(57) **CLAIM**

The ornamental design for a surgical punch, as shown and described.

DESCRIPTION

FIG. 1 is a perspective view of a surgical punch in accordance with the new design;

FIG. 2 is a left side view of the surgical punch of FIG. 1, the right side being a mirror image;

FIG. 3 is a front view of the surgical punch of FIG. 1;

FIG. 4 is a rear view of the surgical punch of FIG. 1;

FIG. 5 is a bottom plan view of the surgical punch of FIG. 1; and,

FIG. 6 is a top plan view of the surgical punch of FIG. 1. The broken lines in the figures are directed to portions of the surgical punch that form no part of the claim.
